UNITED STATES PATENT OFFICE.

ALMA BLOOMA COLE, OF KINGSTON, ILLINOIS.

WHEEL-GUARD.

SPECIFICATION forming part of Letters Patent No. 325,821, dated September 8, 1885.

Application filed July 10, 1885. (No model.)

To all whom it may concern:

Be it known that I, ALMA B. COLE, of Kingston, De Kalb county, Illinois, have invented a new and Improved Wheel Guard, of 5 which the following is a full, clear, and exact description.

The object of my invention is to provide a new and improved wheel-guard for the purpose of preventing persons being run over and 10 killed or mutilated by the wheels of street or railway cars.

The invention consists in the construction and arrangement of parts, as will be herein-after fully described and claimed.

Reference is to be had to the accompanying 15 drawings, forming part of this specification, in which similar letters of reference indicate corresponding parts in both figures.

Figure 1 is a side view of my improved 20 wheel-guard, parts being broken out. Fig. 2 is a plan view of the same.

The guard is constructed with a frame, A, of wrought or cast iron, provided with upwardly-projecting bars B, having their upper 25 ends bent over rectangularly, through which bent ends bolts are passed into the bottom of

the car C for holding the guard on the car, the bottom edges of the guard being a short distance above the rails H. The top edges of the guard are curved downward and toward 30 the rear.

The frame of the guard is covered with sheet metal E, riveted on the frame.

The guard is directly in front of the wheel F, and surrounds part of the same. 35

In case a person falls on the tracks and any part of the body rests upon the rails, it will be struck by the guard before the wheel F can run over it, and is pushed to one side.

The guard is very light and strong, and can 40 easily be attached to any car.

Having thus described my invention, I claim as new and desire to secure by Letters Patent—

A wheel-guard consisting of the metal frame A, having its top curved down toward the 45 rear, the upwardly-projecting bars B, and the sheet-metal covering E, substantially as herein shown and described.

ALMA BLOOMA COLE.
